KNIFE OR SIMILAR ARTICLE

Irving Fiske, New Rochelle, N.Y., assignor to Welling Ware, Inc., New York, N.Y., a corporation of New York

Filed Feb. 25, 1958, Ser. No. 49,789

Term of patent 3½ years

(Cl. D22—3)

Fig. 1 is a top plan view of a knife or similar article, showing my new design.

Fig. 2 is a side view thereof.

Fig. 3 is a bottom plan view thereof.

Fig. 4 is a cross-sectional view taken on line 4—4 of Fig. 1, as viewed in the direction of the arrows.

Fig. 5 is a cross-sectional view taken on line 5—5 of Fig. 1, as viewed in the direction of the arrows.

Fig. 6 is a cross-sectional view taken on line 6—6 of Fig. 1, as viewed in the direction of the arrows.

The characteristic feature of the design resides in the shape and location of the triangular notch or depression on the front and back of the handle, shown in Figs. 1 and 3 of the drawing, wherein the base of the triangle is perpendicular to the longitudinal axis of the handle and coincident with the bottom edge of the handle of the knife.

I claim:

The ornamental design for a knife or similar article, substantially as shown and described.
